UNITED STATES PATENT OFFICE.

WILLIAM A. OGLETHORPE, OF LIVERPOOL, ENGLAND.

SHIP STEERING-GEAR.

SPECIFICATION forming part of Letters Patent No. 499,569, dated June 13, 1893.

Application filed July 13, 1892. Serial No. 439,920. (No model.)

To all whom it may concern:

Be it known that I, WILLIAM ALLAN OGLE-
THORPE, a subject of the Queen of Great Brit-
ain and Ireland, residing at Liverpool, in the
5 county of Lancaster, England, have invented
new and useful Improvements in Ship Steer-
ing-Gears, of which the following is a specific-
ification.

My invention relates to an improved hy-
10 draulic steering and cushioning gear, for the
purpose of placing the rudder in any required
position, and for relieving the rudder and gear
of excessive strains caused by heavy seas.

In the drawings which serve to illustrate
15 my invention, I show examples of steering
gear embodying the combination of all my
improvements.

Figure 1 is a side elevation, Fig. 2 a plan,
20 and Fig. 3 an end view of one example of
gear according to the invention. Figs. 3^A, 3^B,
and 3^C are respectively an elevation partly in
section, a plan, and an end view, of details of
parts of the apparatus shown in Figs. 1, 2 and
25 3. Fig. 4 is a longitudinal section, and Fig.
5 is a plan, illustrating the fluid distribution
valve of the apparatus. Fig. 6 is an outside
elevation and Fig. 7 is an end view of a modi-
fication of the invention. Fig. 8 is a side view
30 and Fig. 9 a plan of another modification.

35 In the different figures and modifications
herein given the same letters of reference are
used to denote the same or like parts wher-
ever they occur in the drawings.

Referring now to the drawings, and more
35 particularly to Figs. 1, 2, and 3, *a* designates
a "duplex" steam pump of any suitable kind,
the action of which is after the well known
manner of this class of pumps known as "du-
plex" pumps, that is, one which may be
40 stopped by shutting off the supply of steam
to it and when the steam is again admitted
to its steam cylinders it will start of itself;
however any pump which will do this may be
used in lieu of a "duplex" one.

45 *b* is a hydraulic cylinder; *c* is the piston
rod of said cylinder, through the covers of
which it works, it being provided with a pis-
ton *b'* within *b* in the usual way.

50 *d* and *e* are crossheads mounted on the pis-
ton rod *c* and provided respectively with pul-
leys or sheaves *f'* *f²*, and *f³* *f⁴*.

g is a liquid reservoir or cistern into which

the liquid is pumped and withdrawn by the
apparatus.

Regarding the parts connected with the 55
pump *a*, *a'* designates a chest within which a
suitable steam supply and cutoff valve *a^x*
works, *a²* being the valve rod thereof. In the
same line with this rod *a²*, and connected
thereto, is a valve rod *h'* of the oil or other 60
liquid distribution valve *h* (see Figs. 4 and 5).

a³ is the feed or intake pipe of the pump,
the feed being taken from the tank *g*.

a⁴ is the pump delivery branch which con-
veys the liquid from the pump to the center 65
of the valve *h*.

h² are pipes leading from the valve *h* to the
opposite ends of the cylinder *b*, and by which
the liquid is conveyed to and from the said
tank and the valve. The relief valves *i^x* to 70
the cylinder *b* (which are of the ordinary "lift"
type) are provided at each end thereof in the
valve casings *i*, and the liquid which may be
forced past said valves at any time, is con-
veyed out of said casings into the tank *g* by 75
the pipes *i'*.

i² are the spindles of these two valves, and
these two spindles are normally pressed away
from each other, and the valves kept upon 80
their seats, by a single spring *i³*.

For convenience, the pipes *h²* communicate
with the ends of the cylinder *b* by way of the
valve casings *i* of the relief valves, such com-
munication or passage being of course dis-
posed on the cylinder side of such valves. 85

As regards the chain or rope connecting the
apparatus with the tiller of the rudder, one
end of said chain or rope is shown in dotted
lines and designated *x*. It is fixed to the ap-
paratus, say at *y* (Figs. 1 and 2) and passes 90
over the smaller pulley *f⁴* of the two on the
crosshead *d*, then back round one of the pul-
leys *j* mounted on the cylinder *b*, then over
the larger pulley *f³*, on the crosshead *d*, and
then back and away to the tiller to which it 95
is fixed. In a like manner the other end of
the chain will be fixed to the apparatus in the
same manner, and passes over the pulley *f⁴*,
then over the other pulley *j'*, then over *f²*,
and back, and to the tiller. To obtain these 100
passings and runnings of the chains or ropes,
so that the pistons should be subject to no
oblique stresses, and to avoid the different
parts of these from touching or rubbing

against each other, the axes of the pulleys in the crossheads d are set at an inclination to each other, while the two of them, f' and f^4 , are made smaller than the other two f^2 and f^3 . The pulleys j j^2 are also disposed on axes at different angles in order that the chain or rope shall lie parallel with the center line and direction of motion of the piston rods c .

To actuate the steam supply and cut off valve a' , and admit steam to the cylinders of the pump a , the valve rod a^2 is connected up to a hand steering mechanism m shown in Fig. 3 through the device I will now describe:—Onto a bracket k , I mount a bell crank lever k' , having at one end of it a nut k^2 , through which the screwed end l' of the rod l from the steering mechanism m works. To the other end of the bell crank I attach, by a pin joint connection n^3 , a duplex lever n , the lower end of which is connected to the cross-head d by the rod n' ; and to this lever n , at a small distance below its joint n^3 with the bell crank lever k' , namely, at n^2 , are fixed or mounted rods k^3 , the other ends of which are connected to the valve spindle a^2 . This mechanism operates somewhat after the manner of an ordinary marine engine reversing gear cut off mechanism, that is, when the bell crank lever k' is moved either one way or the other by the actuation of the hand steering mechanism m , it moves the upper end of the lever n , and so, through the connecting rods k^3 , gives movement to the steam admission valve a^2 of the pump a and admits steam therein. At the same time it moves the valve h , and the liquid from the pump a is distributed to one or other end of the cylinder b , according to the direction in which the hand wheel of the steering gear is moved, and the rod l rotated. The consequent movement of the piston rods c and crosshead d , is, that the rod n' moves the lever n , and so the connecting rods k^3 are moved in the opposite direction to which they were moved by the movement of the bell crank k' , and the steam supply valve in a' is actuated and cuts off the supply of steam to the pump, and at the same time brings the valve h to the central or neutral position and locks the liquid in the cylinder b .

It may be here stated that the pump a always works in the same direction, and it is only in the distribution of the liquid from the pump by the valve h that the reversal of direction of motion of the piston rod and pulleys supported thereon is effected. By thus adapting the pump to be set in motion and stopped as and when desired, no accumulator is required.

Referring to the construction of the valve h shown in Figs. 4 and 5, it will be seen that it consists of two pistons o o' , connected together by the parts o^2 , which in turn are connected to or from part of the valve rod h' . The position of the valve shown in the drawings is its central or neutral one, and is that which it takes when the pump is stopped and the liquid locked in the opposite ends of the

cylinder b . When, however, the valve is moved as just described, the liquid from the pump passes by way of the delivery pipe a^4 70 thereof into the central part of the valve and between the pistons o o' , and thence to one of the branches o^3 , whichever of the two may be in communication with a^4 , to one end or other of the cylinder b , through one of the 75 pipes h^2 ; while the other of the branches o^3 will be in communication with one of the branches o^4 , which communicate with the tank g through the pipes h^3 ; and thus the liquid from the other end of the cylinder b , which is exhausting, would pass by the communication thus formed to the tank g , from which it would be drawn by the pump through the return or feed pipe a^3 . Thus it will be seen, that, accordingly as the valve h is moved in 85 one direction or the other by the action of the steering mechanism m , the liquid flows by one or the other of the branches o^3 , and so to one or other of the ends of the cylinder b ; and that the other of said branches o^3 becomes, for the 90 time being, the exhaust branch by which the liquid from the other end of said cylinder is passed to the tank g .

Generally then, the whole operation of this apparatus is as follows:—When it is desired to change the position of the rudder, the hand steering mechanism m is moved in the desired direction, whereupon, steam is given to the pump a by the opening of the valve in a' , and it is set in motion. Liquid is so drawn 100 from the tank g and forced through the valve h to one or other end of the cylinder b , according to which direction it is desired to move the piston thereof, and the crossheads and pulleys thereon, the discharge of liquid 105 from the opposite end of the cylinder being adapted to take place through the valve h into the tank g . The result of the movement of the piston and the pulleys connected on the end of the piston rod c thereof is, that the 110 chain or rope x is taken up by one set of the pulleys (f' f^2 or f^3 f^4), and the same amount is paid out by the other set of pulleys. Of course the tiller (to which the chain or rope is connected in any known way), and with it 115 the rudder, is moved by the chain or rope taken up by the out traveling pulleys, and the chain or rope on the inwardly traveling pulleys is paid out to the tiller.

In case a sea strikes a rudder with abnormal force, shock, and consequent straining thereof, is prevented or obviated by the relief valves i , which lift by the abnormal pressure thereby brought upon them, and allow liquid to pass from that end of the cylinders 125 in which such liquid is subjected to the said abnormal pressure. The liquid thus relieved passes into the tank g . The movement of the pistons and crossheads, due to this cause, effects the actuation and opening of the steam 130 supply valve in a' through the rod n' , lever n and links k^3 ; the pump will therefore be set going, and will force liquid into that end of the cylinder from which it had been forced

by the striking of the rudder by the sea, until the position it stood at when the incident happened, is reached.

- In the modification shown in Figs. 6 and 7, the crossheads *d* and *e* are each provided with a single pulley instead of two, as in Figs. 1 to 3. In this case the center of the axes of these pulleys lies coincidentally with the center or axes of the piston rods *c* and cylinder *b*, while the vertical planes in which said pulleys *f*' *f*² lie cross each other as shown. The pulleys in this case are of the same size. This arrangement is designed to prevent the part of the chains *x* passing round the pulleys *f*' and *f*², from fouling each other, and to cause the pressure on the piston rods *c* to pass through its center or axes. Otherwise than in this respect this apparatus is the same as that shown in Figs. 1 to 3.
- As regards the position or arrangement of the steering gear shown in Figs. 1 to 7 in relation to the rudder, it is to be observed that it may be placed at any desired part of the ship, as the chains *x* may be led and guided as desired.

In the modification shown in Figs. 8 and 9, the two cylinders *b*, and rams, *c*, are used in lieu of one; but in this case they are single acting, and the rams are directly connected to the tiller of the rudder. Otherwise than in this respect, this apparatus is the same as that shown in Figs. 1 to 3. In these Figs. 8 and 9 the relief valve casings *i* and their pipes *i*', and springs *i*², are shown, as are also the pipes *h*² which connect the valve *h* with the cylinder *b*, and by which liquid is conveyed to and from said cylinders.

The rudder head is designated *r*, and the tiller *s*, the connection of the rams *c* (which are coupled together as shown) to the tiller being effected by a sleeve *t* working on the rounded end of such tiller, and by trunnions or journals *t*' working in the coupling of the rams *c*, as shown. The coupling of these rams constitutes a loop around the tiller.

Having now particularly described and ascertained the nature of this invention, and in what manner the same is to be performed, it is to be understood that this invention is not confined to the particular construction of parts herein set forth with reference to the drawings, nor to the particular constructions or disposition of said parts, but

What is claimed in respect of the herein described invention is—

1. Steering gear for ships comprising the combination of a duplex or equivalent steam pump, a hydraulic ram apparatus such as described, connected with the rudder, a tank into which the ram apparatus discharges or exhausts its liquid, and from which the pump draws liquid, and suitable inlet and outlet pipes connecting said hydraulic ram apparatus and pump with said tank, the steam pump being adapted to be started and stopped and to force liquid into said hydraulic apparatus and move the rudder in one direction

or the other, substantially as and for the purposes set forth.

2. Steering gear for ships, comprising a duplex steam pump, hydraulic ram apparatus such as described, a tank into which the ram apparatus discharges or exhausts its liquid, and from which the pump draws liquid, and suitable inlet and outlet pipes connecting said hydraulic ram apparatus and pump with said tank, and automatic cut off mechanism operated by the action of the said hydraulic apparatus by which the steam supply to the pump is automatically controlled, operating substantially as and for the purposes set forth.

3. Steering gear for ships comprising a cylinder, a piston working in said cylinder having a double piston rod working through both ends of the said cylinder, and a pulley or pulleys on the end of each piston rod, and chains or ropes working over said pulleys and cylinder, as described and connected with the rudder tiller; operating substantially as set forth.

4. Steering gear for ships comprising a steam pump, and a hydraulic cylinder or cylinders with rams or piston rods with a pulley or pulleys on both ends thereof, and chains or ropes working over said pulleys and crossing each other or running in opposite directions, said pulleys being of different sizes, or disposed angularly to each other as set forth, whereby such chains or ropes are adapted to pass each other without fouling and to cause the stress to pass through the center of said rods or rams.

5. In a steering gear for ships, the combination of a "duplex" steam pump; a hydraulic cylinder or cylinders; a liquid distribution valve by which the liquid from said pumps is distributed to said hydraulic apparatus and moves it in one direction or the other; a steam controlling valve to set said pump in motion; a starting and controlling mechanism actuated by hand by which said steam valve is actuated; an automatic cut off device operated by the hydraulic cylinder by which said steam supply valve is reversed, steam cut off, and the pump stopped; and a tank *g* connected by suitable pipes with the hydraulic cylinder or cylinders and the liquid distribution valve and into which exhaust or escaping liquid is passed, and from which the pump draws its liquid; substantially as set forth.

6. In hydraulic steering gear, the combination of a steam pump to force the liquid, a hydraulic ram apparatus such as described connected thereto and actuated by the liquid forced by the pump, a hand operated mechanism by which the steam supply valve of the pump is open to any degree according to the amount it is required to turn the rudder, and an automatic cut off mechanism operated by said hydraulic apparatus and by which after the rudder has been moved the said desired amount by the actuation of said hand operated mechanism, the supply of steam to the pump is automatically cut off as soon as

the rudder reaches the position required, and the liquid in the hydraulic apparatus locked therein.

7. Steering gear for ships comprising a steam pump; a hydraulic apparatus such as described operated by said pump; a steam supply controlling valve; a liquid distribution valve connected with said pump and hydraulic apparatus; liquid relief valves on said hydraulic apparatus; and an automatic valve operating mechanism adapted to move and set said steam and liquid distribution valves by the movement of said hydraulic apparatus

when the ship's rudder and said hydraulic apparatus have been moved by the action of a sea ¹⁵ striking the rudder, and by which the rudder will be moved back to the position it originally stood in: substantially as and for the purposes set forth.

In testimony whereof I hereunto affix my ²⁰ signature in presence of two witnesses.
